TOY MARBLE CONVEYING MACHINE
 Eldon F. Bjork, 3204 Wright St., Des Moines, Iowa
 Filed Aug. 1, 1963, Ser. No. 299,385
 10 Claims. (Cl. 46—42)

This invention relates to toys and particularly to a toy marble machine.

Children, and adults too, are usually fascinated by mechanical devices which have many moving parts which may be seen in operation.

Therefore it is an object of this invention to provide a toy marble machine which through a number of conveyors continuously moves marbles or the like;

It is a further object of this invention to provide a toy marble machine which uses over and over again the same group of marbles or the like;

It is a further object of this invention to provide a toy machine which will subject marbles or the like to a number of different handling operations;

It is a further object of this invention to provide a toy machine which may be manually operated;

It is a further object of this invention to provide a toy machine which involves a number of moving parts which may be visually seen;

It is a further object of this invention to provide a toy marble machine having a signalling device which sounds periodically during its operations;

It is a further object of this invention to provide a toy marble machine having its own storage compartment for the marbles when they are not in use;

It is a further object of this invention to provide a toy marble machine which will be educational to the operator through observing its operation;

A further object of this invention is to provide a toy marble machine which is simple in design, economical to manufacture and refined in appearance.

This invention consists in the construction, arrangements, and combination, of the various parts of the device, whereby the objects contemplated are attained as hereinafter more fully set forth, specifically pointed out in the claims, and illustrated in the accompanying drawings, in which:

FIG. 1 is a side perspective view of the toy marble machine of this invention;

FIG. 2 is a fragmentary perspective view of the outlet end of the feed gravity conveyor and in particular showing a marble held therein by a releasable gate pin;

FIG. 3 is a fragmentary perspective view of the scoop member on the end of the balance arm in a position wherein a marble is being ejected therefrom; and

FIG. 4 is a fragmentary perspective view taken along the back side of the marble machine as shown in FIG. 1 to illustrate the construction and operation of the signalling device which is actuated by the balance arm.

The marble machine is generally referred to in FIG. 1 by the reference numeral 10. It is shown to comprise a gravity conveyor 12 which discharges marbles 13 into a scoop member 14 on the end of a balance arm 16. An ejector 18 removes the marbles from the scoop where they are then received by a gravity conveyor 20. An endless belt conveyor 22 then returns the marbles to the feeder conveyor 12.

A straight sided frame 24 with rounded ends 25 and 25' is provided for the machine 10 and rests upon four legs 26 positioned at each of its corners. A compartment 28 is formed in the base of the frame 24 under the conveyor 20 and has an access opening (not shown) through which the marbles may be placed when not in use for storage.

The conveyor 20 is channel shaped in cross-section and U-shaped in plan (FIG. 1) and has an inlet end 30 raised relative to its outlet end 32. At the inlet end 30, the ejector member 18 is provided. The ejector is generally in the shape of an inverted V, having one flat leg 34 secured to the bottom of the channel conveyor 20 with its other leg formed with a concave portion 36 adjacent the vertex of the V and terminating in a concave portion 38 at the lower end of the leg where it is secured to the base of the conveyor channel 20.

A housing 40 encloses on the sides the continuous belt conveyor 22. The lower end 42 of the conveyor 22 is adjacent the outlet end 32 of channel 20 and a discharge end 44 is disposed upwardly and rearwardly therefrom. A plurality of paddles 46 are uniformly spaced and secured along the outside surface of the continuous belt conveyor 22. Each of the paddles 46 are concave on one side and have a central opening 47 to nestingly receive the marbles 13. A crank member 48 is provided at the lower end of the continuous belt conveyor 22 and is intended to be operated in a clockwise direction when viewing the machine as illustrated in FIG. 1. The housing 40 has a guard member 50 at the upper end to guide the marbles 13 into an inlet end 51 of the conveyor 12.

Conveyor 12 is affixed to the bottom of the guard 50 and is supported by a member 52 in a position such that the inlet end 51 is higher than the outlet end 54. Thus, the marbles 13 will move from the end 51 to the end 54 by gravity. The conveyor 12 is also channel-shaped in cross-section similar to the conveyor 20 and U-shaped in plan. At the outlet end 54, a downwardly directed spout 56 is provided and has a gate pin 58 extending transversely thereof and movable vertically in a pair of slots 60 formed in the sidewalls of the channel. When the pin 58 is down, the marbles are prevented from passing out the spout 56.

The bottom of the spout 56 is normally telescopically embraced by the scoop 14 (FIG. 1). It has a pair of walls 62 and 64, and endwall 66 with an opening 68 formed therein. A bottom wall 70 is provided with a cut out portion 72 which extends into the bottom portion of the end wall 66.

The scoop member 14 is provided on one end of the balance arm 16 which is pivotally mounted intermediate its ends to a member 74 which also supports the conveyor 12 and rests on the base frame 24. The other end 76 of the arm 16 (FIG. 4) carries a balance weight 78 which is adjustable therealong by releasing screw 80.

Adjacent the end 76 of the balance arm 16 is a bell 82 secured to the frame 24. A bell striker 84 is provided on the end of a pivotal support rod 86 which in turn is pivotally secured to the frame 24 by a bearing mounting 88. A portion 90 of the rod 86 extends directly behind the bell 82 and is semicircular in shape to accommodate the circular shape of the bell. On the opposite side of the bearing 88 from the portion 90 is a rod portion 92 which extends upwardly and has a roller member 94 mounted thereon for engagement by the balance arm end 76 when the arm is in its normal position as shown in FIG. 1.

In operation, marbles 13 may be taken from the storage compartment 28 and placed initially in either the channel conveyor 12 or 20. If the marbles are first placed in the channel conveyor 20 they will be carried by the paddles 46 to the conveyor 12 upon rotation of the crank 48. Since the conveyor 20 is of the gravity type, marbles placed at any point therein will move into engagement with the conveyor belt 22 to be engaged by one of the paddles 46. The feed conveyor 12 is also of the gravity type and the marbles will follow the U-shaped course of the conveyor

and line up against the gate pin 58. As shown in FIG. 1, the sides 62 and 64 normally engage the ends of the gate pin 58 to hold it in its upper position within the slots 60 thereby permitting a marble 13 as shown in FIG. 2 to drop through the spout 56 into the scoop 14. The weight of a marble will shift the center of gravity of the balance arm 16 to the scoop 14 thereby causing the balance arm to pivot downwardly. The gate pin 58 is simultaneously dropped to prevent any additional marbles from being released from the conveyor 12 until the scoop 14 has returned. As the balance arm 16 moves to its lowermost position as shown in FIG. 3, the ejector member 18 is received through the cutaway portion 72 and contacts the marble 13 along the concave portion 36 of the ejector to push the marble 13 upwardly and outwardly through the opening 68 in the end wall 66 of the scoop 14. The marble 13 is then received by the conveyor channel 20 where it begins its return trip back to the endless conveyor belt 22.

Referring now to FIG. 4, it is seen that the end 76 opposite the scoop 14 on the balance arm 16 strikes the roller 94 each time the balance arm moves to the position shown in FIG. 1 to receive a marble 13. This striking action causes the support rod 86 to pivot upon impact and move the bell striker 84 into impact engagement with the bell 82. When the balance arm 16 is in the position as shown in FIG. 3 wherein the scoop 14 is lowered adjacent the ejector 18, the bell striker 84 moves rearwardly on the support rod 86 to be ready for striking the bell 82 once the balance arm 16 has returned to its position of FIG. 1 to receive another marble 13.

Some changes may be made in the construction and arrangement of my toy marble conveying machine without departing from the real spirit and purpose of my invention, and it is my invention to cover by my claims, any modified forms of structure or use of mechanical equivalents which may be reasonably included within their scope.

I claim:

1. A toy marble machine, comprising:
a first marble conveyor having a discharge station;
a pivotal balance arm having a scoop on one end, means
for normally pivoting said arm to an up position with
said scoop in communication with said discharge
station to receive marbles from said scoop, said arm
pivoting to a down position upon a marble being
placed in a said scoop;
a gate member provided in said first conveyor adapted
to be operatively opened by said balance arm to permit
discharge of marbles into said scoop;
an ejector member positioned in the path of pivotal
movement of said arm for communication with said
scoop when said arm is in said down position only;
a second conveyor to receive said marbles from said
scoop, and said ejector member engaging said
members when said arm is in said down position for
ejecting them into said second conveyor; and
means for returning said marbles to said first conveyor.

2. The structure of claim 1 wherein said scoop has an opening in its bottom side and an opening in one of its side walls, and said scoop is adapted to telescope onto said ejector member through said bottom opening and engage said marble for ejecting it out of said scoop through said side wall opening into said second conveyor, and said balance arm returns to said first position to receive another marble.

3. The structure of claim 1 wherein said first and second conveyors are characterized as being of the gravity type.

4. The structure of claim 1 wherein said gate member is a pin extending across said discharge station for closing it to passage of marbles, guide means for guiding said pin between up and down positions, and said scoop engaging and raising said pin above said marbles when said arm is in said up position for opening said discharge station

5 to permit a marble to move into said scoop and said scoop being adapted to pivot on said balance arm away from said discharge station whereupon said pin returns to its closed down position preventing passage of marbles through said discharge station.

5. The structure of claim 1 wherein said means for returning said marbles to said first conveyor comprises an endless belt having a plurality of paddles, said second conveyor being in communication with the endless belt for discharging marbles thereon to be carried by said paddles to said first conveyor and discharged thereon.

6. The structure of claim 1 wherein said means for returning said marbles to said first conveyor comprises an endless belt having a plurality of paddles, said second conveyor being in communication with the endless belt for discharging marbles thereon to be carried by said paddles to said first conveyor and discharged thereon, and means for operating said endless belt conveyor.

7. The structure of claim 1 including sound means adapted to be actuated by said balance arm each time said arm moves to said up position.

8. A toy marble machine, comprising:
a first marble conveyor having a discharge station;
a balance arm means pivotally supported intermediate
its ends and one end having a scoop member while
the other end carries a weight member for maintaining
said arm means in a first position wherein said
scoop is normally adjacent said discharge station,
said scoop and said discharge station being in com-
munication with each other for said scoop to receive
marbles from said station;

a bell having a striker element connected to supporting
arm means, said supporting arm means being adapted
to be struck by the other end of said balance arm
means as said scoop moves to its position adjacent said
marble discharge station to move said striker ele-
ment into contact with said bell thereby causing it
to ring;

an ejector member positioned below and in the path of
said scoop, and said balance arm means adapted to
pivot downwardly adjacent said ejector member upon
said scoop receiving a marble and said ejector con-
tacting said marble in said scoop to discharge it
therefrom;

second conveyor means adapted to receive said marbles
ejected from said scoop; and
means for returning said marbles to said first conveyor
from said second conveyor.

9. The structure of claim 8 wherein said machine has
a supporting frame with a compartment therein for stor-
age of said marbles.

10. A toy marble machine, comprising:
a first marble conveyor having a discharge station;
a balance arm means having a scoop means on one
end, and said scoop means adapted to be in communi-
cation with said discharge station to receive marbles;
a gate member provided in said first conveyor adapted
to be operatively opened by said balance arm means
to permit discharge of marbles into said scoop
means;
an ejector member adapted to be in communication
with the inside of said scoop means to eject said
marbles;

a second conveyor means adapted to receive said
marbles from said scoop means;
means for returning said marbles to said first conveyor;
said balance arm means being pivotally supported and
balanced so that it normally is pivoted to a first
position wherein said scoop means is adjacent said
discharge station for receiving a marble, and upon
receiving a marble is pivoted to a second position
adjacent said ejector member;

said ejector member being in the shape of an inverted V and positioned below said scoop means, and said scoop means having an opening in its bottom side and an opening in one of its side walls, and said scoop means being adapted to telescope onto said ejector member through said bottom opening and engage said marble for ejecting it out of said scoop means through said side wall opening into said second conveyor means, and said balance arm means returns to said first position to receive another marble.
